UNITED STATES PATENT OFFICE.

RANDOLPH DOUGLAS GIFFORD, OF CHINGFORD, ENGLAND, ASSIGNOR TO MESSRS. NALDER BROTHERS & THOMPSON, LIMITED, OF LONDON, ENGLAND, A CORPORATION OF ENGLAND.

ALTERNATING-CURRENT ELECTRICAL INSTRUMENT OF THE MOVING-COIL TYPE.

1,237,775.

Specification of Letters Patent. Patented Aug. 21, 1917.

Application filed January 18, 1915. Serial No. 2,907.

To all whom it may concern:

Be it known that I, RANDOLPH DOUGLAS GIFFORD, subject of the King of Great Britain and Ireland, residing at Chingford, 5 Essex, England, have invented certain new and useful Improvements in Alternating-Current Electrical Instruments of the Moving-Coil Type, of which the following is a specification.

10 My invention relates to improvements in electrical instruments of the moving coil type (in which the moving element consists of or includes a conductor traversed by an alternating current or a rectified alternating current or a varying or interrupted continuous current) such for example as ammeters, voltmeters, wattmeters, phase indicators, synchronizers, and the like. In such instruments current is usually led to the moving 15 active element by means of metallic conductors, a method which has several drawbacks among which is the fact that the moving active element is controlled and restricted. Or the current has been introduced by brushes which has the drawback that friction is introduced. Or the current has been introduced by induction but in such a way that an action is set up between the 20 circuits carrying inducing and induced currents respectively tending to produce movement.

My invention is designed to obviate these drawbacks and it consists in connecting the moving active element of the instrument materially with the secondary winding of a transformer having no mechanical connection with its iron circuit or the primary winding thereof, no action being set up between the inducing and induced circuits 25 which will tend to produce or restrain movement.

In order that my invention may be readily understood I shall now proceed to describe by way of a type or example one form 30 thereof and to aid such description I append hereto a sheet of drawings which diagrammatically illustrate the principle of my invention.

In the said drawings Figure I is a part 35 section, part elevation and Fig. II a plan.

The straight line 1 represents the angularly moving spindle of the instrument and upon it I mount the disk 2 (preferably of non-conducting material) and at the edge

of this disk I place a circular coil of wire 55 3 concentric with the spindle 1 and the ends 4, 5 of which coil are connected with the moving active element 6 of the instrument. The insulating disk passes without touching through a small gap 7 in the iron circuit 60 8 of a small transformer of which the coil 3 forms the secondary. The iron circuit is provided at another part with a primary winding 9. The circular coil being concentric with the spindle of the instrument it can 65 rotate with the latter (through more than a complete revolution if so desired) without in any way changing its position relatively to the magnetic circuit of the transformer. Consequently in so far as the currents flowing in the primary and the secondary are concerned, there is no tendency to rotate the spindle in either one direction or the other, or to hold it in any one position. In other 70 words the transformer will not in any way 75 affect the movement of the spindle caused by the moving active element.

It will be understood that the present invention is not limited to the typical form thereof described. Thus a secondary coil of 80 some shape other than circular might be employed provided that the magnetic circuit is such that the departure from circularity does not cause any turning moment in the secondary coil of the transformer. Fur- 85 ther, I may employ a transformer in which there is no iron circuit but in which the magnetic circuit is of air for example.

By the present invention the current 90 which it is desired to introduce into the moving active element is brought in without any control or restriction or friction, or inductive effect tending to produce movement.

It will be seen that by means of my invention as hereinbefore described a current may 95 be introduced into the moving active element by variations or interruptions in the strength of a continuous current flowing in the primary of the transformer.

I use the term "iron circuit" in its generic 100 sense and not as implying that the magnetic circuit which it constitutes is made of the metal iron.

It is obvious that my invention is applicable to polyphase as well as to monophase 105 work.

It will be understood that it is not necessary to support the secondary coil upon a

disk. It might be supported for example on a spider or even a single bar placed diametrically with respect to the secondary coil.

5 It is to be noted that my invention involves no mechanical obstacle (such as conducting wires or other parts) to free rotation of the spindle and its attached parts.

10 My invention is particularly useful in the case of power factor meters.

Having thus described my invention what I claim as new and desire to secure by Letters Patent is:—

15 1. In an alternating current electrical measuring instrument of the moving coil type, the combination with the moving active element of the said instrument, of a transformer the secondary of which is mechanically connected with the said moving active element but is mechanically disconnected from its primary, the arrangement being such that 20 no torque is set up between the primary and secondary members, substantially as described.

will tend to produce or to restrain movement, substantially as described.

2. In an alternating current electrical measuring instrument of the moving coil type, the combination with the moving active element of said instrument, of a transformer, the secondary of which is circular 30 in shape and is mounted on a shaft connected with said moving active element, but is mechanically disconnected from its primary and rotates within the air gap of said primary, the arrangement being such that 35 no torque is set up between the primary and secondary members, substantially as described.

35 In witness whereof I have signed my name to this specification in the presence of two subscribing witnesses.

RANDOLPH DOUGLAS GIFFORD.
